WATER SERVICE SYSTEM FOR
RAILWAY YARDSWilliam F. Zabriskie, Detroit, and Hoyt Post,
Grosse Pointe, Mich., assignors to Gabriel Steel
Company, Detroit, Mich., a corporation of
Michigan

Application June 12, 1944, Serial No. 539,962

3 Claims. (Cl. 137—78)

The invention relates to water service systems for railway yards and similar installations in which a series of hydrants are provided adjacent to the tracks for use in filling the water tanks of the individual cars. As such systems are used in all seasons of the year, it is essential that they should be located below the frost line to avoid freezing in the winter time. However, as the hydrants extend upward above the frost line, they must be drained when not in use and it has been the practice to discharge the drain water into the surrounding soil. While this method may protect the hydrants from freezing, it has been found that in many locations the drain water will accumulate around the discharge opening instead of passing completely away. As a result, when the hydrant is again used, there is danger that the drain water will be siphoned back and mixed with the water in the tanks. Consequently, sanitary regulations have prohibited the use of such systems.

It is the object of the invention to obtain a system which avoids this defect and which is equally effective in preventing freezing. To this end the invention consists in the construction and method of operation of an improved system as hereinafter set forth.

In the drawings:

Fig. 1 is a diagrammatic plan view illustrating my improved water service system;

Fig. 2 is a vertical central section through one of the hydrants;

Fig. 3 is a similar view showing the construction more in detail;

Fig. 4 is a cross section on line 4—4, Fig. 3; and Fig. 5 is a section on line 5—5, Fig. 4.

The essential feature of our invention is the method of avoiding freezing of the water in the portions of the hydrant which are above the frost line by maintaining the same in constant circulation. Inasmuch as the water in the supply system is at a temperature considerably above the freezing point, all that is necessary to prevent freezing at any point is to maintain the flow. This need not involve the wasting of any water as it may be returned to the supply system after completing the circuit.

As shown in Fig. 1, A, A', A² are tracks in a railway yard and B, B', etc. are hydrants arranged adjacent to these tracks and spaced from each other by substantially the length of a railway coach. C is a water supply conduit buried beneath the frost line and extending successively to all of the hydrants. There is also a conduit D extending from the last of the series of hydrants

to connect with the conduit C at some point in advance of the first of the hydrants. Connected into the conduit D is a pump E driven either electrically or by any other source of power and which maintains a constant circulation of the water.

Each of the hydrants B has at its upper end a service connection F preferably located in a box G at or near the surface of the ground. A valve 10 H is also arranged within the box immediately adjacent to the service connection F, which valve is provided with an operating handle H' and a drain port for the escape of the small quantity of water contained within the casing. Below the 15 valve H is a vertical conduit I divided by a central partition J into upward and downward passages K and K'. At the lower end of the conduit I are nipples L and L' connected respectively to the passages K and K' and adapted to be 20 coupled into the conduit C. Thus, when the pump E is in operation, there will be a constant flow of water through the conduit C which at each of the hydrants will flow upward through the passage K to a point adjacent the valve H and will then 25 flow downward through the passage K'. After passing all of the hydrants the water is returned through the conduit D and reintroduced into the conduit C. The hydrants B are preferably formed of standard pipe sections and other elements 30 welded to each other. As specifically shown, the construction comprises a substantially rectangular section M to the opposite sides of which the nipples L and L' are connected by welding to extend in alignment with each other. M' is a 35 central partition in the section M having a curved lower end portion M² extending to the side of said section and a second curved portion M³ extending to the opposite side of the section, all of these parts being secured to each other by welding. 40 Above the section M is the vertical conduit I which is welded to said section M filling in the corners M⁴ by welded metal. The central partition J is also welded to the partition M'. The upper end of the conduit I is threadedly engaged 45 or welded with a tapered coupling N which, in turn, is threadedly engaged with the valve H. There is also preferably a surrounding pipe section O having an annular head P at its lower end connecting it with the conduit I. This forms a 50 casing for containing heat insulating material which protects all of the structure below the box G. The latter is of the usual construction being provided with a hinged cover G' and preferably with a link G² connected to said cover cooperating 55 with the handle H' to close the valve whenever

the cover is in closed position. The small amount of water which drains from the valve casing will drop to the bottom of the box G and will escape through an aperture G³ therein. Also, a second drain aperture G⁴ is arranged in the side of the box above the bottom thereof and slightly above the ground level.

While we have described our system as particularly designed for use in railway yards, another important use is in trailer camps. In all such places the system will meet all of the sanitary requirements for it is obvious that no water outside of the system can be drawn into the same.

What we claim as our invention is:

1. In a water service system, the combination with a water supply conduit located below the frost line, of means for positively circulating water through said conduit a hydrant connected into said conduit and extending upward therefrom being provided at its upper end with a service fitting and an adjacent valve controlling the same, and means dividing said hydrant into separate water passages connected at their upper ends adjacent to said valve and at their lower ends connected to separate portions of said conduit.

2. In a water service system, the combination with a water supply conduit located below the frost line, of means for positively circulating water through said conduit a hydrant connected into said conduit and extending upward therefrom being provided with a central partition forming separate water passages connected at their lower ends with separate portions of said conduit, a fitting at the upper end of said hydrant connecting said passages to each other, a valve connected to said fitting, and a service discharge fitting adjacent to said valve.

3. In a water service system, the combination with a water supply conduit located below the frost line, of means for positively circulating water through said conduit a hydrant connected into said conduit and comprising an upwardly extending portion divided into separate passages connected at their lower ends with separate portions of said conduit, a fitting at the upper end of said portion connecting said passages with each other, a valve connected with said fitting, a service discharge fitting adjacent to said valve, said valve in its closed position being adapted to drain the water therefrom and from said service fitting, a box enclosing said valve and service fitting, and means providing thermal insulation surrounding the portion of the hydrant below said box and extending down to below the frost line.
